UNITED STATES PATENT OFFICE.

JACOB J. UNBEHEND, OF SYRACUSE, NEW YORK, ASSIGNOR TO JUDSON L. THOMSON, OF SAME PLACE.

SPRING-CLASP.

SPECIFICATION forming part of Letters Patent No. 313,390, dated March 3, 1885.

Application filed January 3, 1885. (No model.)

To all whom it may concern:

Be it known that I, JACOB J. UNBEHEND, of Syracuse, in the county of Onondaga, in the State of New York, have invented new and 5 useful Improvements in Spring-Clasps, of which the following, taken in connection with the accompanying drawings, is a full, clear, and exact description.

This invention relates to that class of spring-clasps in which a plate attached to one of the flaps of a shoe or other article has hinged thereon a tongue adapted to interlock with another plate attached to the other flap and provided with slots, through one of which the tongue 10 passes; and the invention has more particular reference to such of the aforesaid clasps which utilize the lateral flexibility of the tongue-carrying plate for imparting to the tongue the requisite spring action for retaining it interlocked with the slotted plate.

The object of the invention is to simplify and cheapen the manufacture of such clasps, and at the same time render them more durable and efficient in their operation; and to that end my 25 invention consists in the novel construction and combination of the tongue and its carrying-plate, as hereinafter fully described, and specifically set forth in the claims.

In the annexed drawings, Figure I is a side 30 view of my improved clasp, with the interlocked slotted plate shown by dotted lines. Fig. II is a plan view; Fig. III, a front end view of the same; Fig. IV, a detached plan view of the tongue-carrying plate with the tongue 35 removed. Fig. V is a top plan view of my improved clasp, illustrating modifications of the details thereof; and Fig. VI is a detached plan view of the tongue in its modified form.

Similar letters of reference indicate corresponding parts.

B represents the usual slotted plate, with which the tongue T interlocks in the use of the clasp. A denotes the plate on which the said tongue is hinged. This plate I form of a single thickness and with a transversely-divided 45 pintle, a, and with the forward extensions, e e. The severing of the aforesaid pintle a allows the extensions e e to deflect laterally from a point back of the pintle, and thus increases the 50 elasticity thereof. The tongue T, I form with

a sleeve, s, which embraces the pintle a, and thus hinges the tongue on the plate A. In front of the pintle I form the tongue with a forwardly and upwardly curved portion, b, and with lateral projections c c on the edges of 55 said portion b. In swinging the tongue back and forth on its hinge the portion b of the tongue moves up and down between the extensions e e of the plate A, and in said movement the projections c c impinge the inner 60 edges of the extensions e e and crowd said extensions apart, thereby producing a limited locking action, which tends to retain the tongue in its closed and in its extreme open position.

In large-sized clasps, which have to be made 65 of heavy plates, I split longitudinally or bifurcate the hinged end of the tongue, as shown in Figs. V and VI of the drawings, and spread the same apart, so as to cause it, when hinged on the plate A, to exert a lateral pressure 70 against the inner edges of the extension e e and yield to the inward pressure incident to the impingement of the projections c c against the aforesaid extension e e when swinging the tongue back and forth on its hinge.

I am aware that prior to my present invention the tongue T has been hinged on a pin held between the two leaves of a doubled plate, and said plate had end extensions, between which a broadened portion of the tongue passed in 80 opening and closing of the clasp; but such a construction and combination of parts rendered the manufacturing of the clasp expensive; also, did not afford to the pintle the requisite secure hold on the doubled plate; also, necessitated the placing of the pintle too great a distance from the free end of the plate in order to form back of the elastic end extensions the eye for the reception of the pintle; and, furthermore, it did not afford to the end extensions the requisite flexibility to yield to the 85 impingement of the lateral projections on the edges of the tongue when swinging the same back and forth on the hinge—all of which defects are obviated by my improvements.

Having described my invention, what I claim is—

1. The plate A, formed with the divided pintle a and with the forward extensions, e e, in combination with the tongue T, formed with 100

the sleeve *s*, embracing the pintle, and with the forwardly and upwardly curved portion *b* and lateral projections *c c*, adapted to impinge the inner edges of the extensions *e e*, substantially as described and shown.

2. In combination with the plate *A*, provided with the extensions *e e*, the tongue *T*, hinged between said extensions and bifurcated longitudinally, and formed with the forwardly and upwardly curved portion *b*, and with the projections *c c* on the edges of said curved portion, substantially as described and shown.

In testimony whereof I have hereunto signed my name and affixed my seal, in the presence of two attesting witnesses, at Syracuse, in the 15 county of Onondaga, in the State of New York, this 26th day of December, 1884.

JACOB J. UNBEHEND. [L. S.]
